VACUUM BASE FOR APPLIANCES OR THE LIKE

Joseph Rubinstein, Newburgh, N.Y., assignor to General Slicing Machine Company, Inc., Walden, N.Y., a corporation of New York

Filed July 15, 1964, Ser. No. 80,888

Term of patent 14 years

(Cl. D54—13)

FIG.3

FIG. 1 is a perspective view of a vacuum base for appliances or the like, showing my new design, the showing of a food slicing machine in broken lines being for illustrative purposes only;

FIG. 2 is a top plan view thereof; and

FIG. 3 is a section taken at lines 3—3, 3'—3', or 3''—3'.

I claim:

The ornamental design for a vacuum base for appliances or the like, substantially as shown and described.
